UNITED STATES PATENT OFFICE.

JOHN LINCOLN GISH, OF SOUTH BEND, INDIANA.

REGULATED AUTOMATIC-CLOSING VALVE.

1,042,547.

Specification of Letters Patent.

Patented Oct. 29, 1912.

Application filed December 28, 1911. Serial No. 688,832.

To all whom it may concern:

Be it known that I, JOHN LINCOLN GISH, a citizen of the United States, residing at South Bend, in the county of St. Joseph 5 and State of Indiana, have invented a new and useful Regulated Automatic-Closing Valve, of which the following is a specification.

The object of my present invention, is to 10 construct, a "regulated automatic closing valve" in such a manner; firstly, that the water in the tank, will be retained under direct pressure, until the said water is required for flushing; secondly, that the water 15 in the tank will be discharged in a large volume, under direct pressure, into and through the valve-casing; thirdly, that the flushing stream, after passing the outlet in the valve-casing, performs no other work, or 20 function, but that of flushing; and fourthly, after the flushing has been completed, for the "regulated automatic closing valve," 25 to be closed automatically, the apparatus be ready, to repeat its work, as hereinafter described.

Figure 1., is a perspective of my improved apparatus. Fig. 2., is a vertical section thereof, with the valves D., and K., in the closed position. Fig. 3., is a vertical section thereof, with the valve D., open, and the valve K., closed. Fig. 4., is a vertical section thereof, with the valves D., and K., in the open position. Fig. 5., is a vertical section thereof, with the valve D., closed, and the valve K., in the open position.

In the drawings, self closing valves, of the reciprocating type are shown.

Like letters of reference, refer to like parts, in the several figures.

In Fig. 1.—E., is the tank, fastened fluid tight, to the removable valve-casing T. I., is the inlet to the tank E. T., is the valve-casing. P., is a face-plate, fastened fluid tight, to the valve-casing T. H., is a handle; 45 C., is a counter-balance, to the handle H.; a., is a set-nut joining the handle H., to an operating spindle, which passes through the face-plate P. O., is the outlet, to the valve-casing T. The usual connections, with the service pipe and the discharge pipe are 50 made at I., and O., respectively. A., is a supporting arm projecting from the inside of the valve-casing T., and engaging the spindle S. S., is an operating spindle, which passes through the face-plate P., (Fig. 1.) at a. B., is a finger, firmly fixed,

upon the spindle S. d., is a valve-stem, to the relief-valve D. D., is the relief-valve, to the main valve K. d', is the valve-seat, to the valve D. o., o', o'', is an inlet, a 60 passage-way, and an outlet opening, through the valve-stem d., for ventilating the valve D., when opened. m., is an adjustable weight, attached to the valve-stem d., by the set-pin i. n., n', is a plate, of a suitable 65 nature, to hold the valve-seat material d', into place. K., is the main valve; K', is its valve-seat. T', is a removable casing, which incloses the main valve K., and forms, a part of the valve-casing T. O', O'', are 70 inlets, to the valve-casing, part T', from the tank E. X., is a chamber, within the casing T', above the valves D., and K.

The special features of my device are described, as follows:—The main valve K., is a 75 heavy weighted valve, (not buoyant), which slides up and down in the valve-casing T', in such a manner, so that, it is only, by or with great pressure, that air or water, can be forced or filtered, between the outer wall 80 of the valve K., and the inner wall of the casing T'. The said valve K., has a concave bottom of such a degree, that a thin cutting edge, is formed, on the bottom of said valve K. Said cutting edge, contacts with the 85 valve-seat K'; the valve-seat K', being made of any suitable material, which will allow the said, thin cutting edge, of the valve K., to be impressed therein, and thereby, form a positive seating or closure. The 90 weighted vent-valve D., has a concave bottom, forming a thin cutting edge, which contacts with the valve-seat d'; the said valve-seat d', being made of any suitable material, which will allow the said, thin cut- 95 ing edge, of the valve D., to be impressed therein, and thereby, form a positive seating or closure. The said vent-valve D., has a valve-stem d., projecting through the central axis, of the main valve K., entirely fill- 100 ing the aperture through which it passes; and yet, the said valve-stem d., is allowed to slide up and down, in its passageway, through the main valve K.; but, when the vent-valve D., is opened, no air or water, 105 can pass, between the outer surface of the said valve-stem d., and the inner wall or surface, of the aperture through which it passes. Hence, by such a construction as stated above, the vent-valve D., is assured of 110 a positive seating or closure, upon its valve-seat d', providing the adjustable weight m.,

is attached to the valve-stem d ., by the set-pin i ., as will be explained below.

With such a close co-adaptation of surfaces, of the valve D ., and its valve-stem d ., 5 with the valve K ., and yet, give ventilation to the valve D ., when opened, it is necessary to provide a passage-way, for such ventilation. And this is accomplished as follows;— At a point, below the under surface of the 10 vent-valve D ., there is an inlet opening o ., into the said valve-stem d .; this said inlet opening o ., is continued, downward, into a passage-way o' ., on the inside of the valve-stem d ., and ends in an outlet opening o'' ., 15 near the lower end, of the said valve-stem d ., thereby, providing complete ventilation for the vent-valve D ., when said valve D ., is opened. It is also a noticeable feature, that when the vent-valve D ., is closed, the passage-way o ., o' ., o'' ., has a double closure, by 20 means of the valve D ., with its valve-seat d' ., and by reason of the fact, that the inlet o ., in the valve-stem d ., has passed below the upper surface of the valve K ., and down 25 into the aperture through which the valve-stem d ., passes; thereby, making a double guard, against leakage, by way, of the vent-valve D . As to the adjustable weight m ., which is attached to the valve-stem d ., by 30 the set-pin i ., the said weight m ., performs special work, besides acting as a stop, to limit the distance, the valve D ., is raised from its valve-seat d' .; or to act as a part of the means, which raises the valve K ., after 35 the valve D ., has been opened;—namely, the said weight m ., is the force or means, which draws quickly, the valve-stem d ., back to its starting position, thereby assuring a quick and positive reseating of the valve D ., after 40 the means, for opening, the valve D ., has broken contact, with the valve-stem d .; and also, after the valve D ., has been reseated, by the action of the weight m ., the said weight m ., holds the vent-valve D ., upon its 45 valve-seat d' ., as the main valve K ., descends to its valve-seat K' .; thereby offering a greater resistance to the air, which is trying to reenter the chamber X ., through the passage-way o ., o' ., o'' ., and by way of the 50 valve-seat d' ., as the main valve K ., descends to its valve-seat K' .

In the act of the opening of the valves D ., and K ., we displace through the passage-way o ., o' ., o'' ., the air and water, that may 55 have been confined within the chamber X . Now, by a prearranged relation of parts, we allow the valve D ., to close, and leave the valve K ., suspended within the casing T' ., see Fig. 5. This suspended relation, of 60 the heavy weighted valve K ., Fig. 5., is in proportion, to the assembling of the parts, T' ., K ., D ., d ., d' ., n ., n' ., and m .; whereby we govern, the balancing of the force of gravity, which acts upon the valves, and the 65 pressure beneath said valves. And this is

accomplished, by having the device so constructed, and the parts so assembled, that it is only, by or with great pressure, that air or water, can be forced or filtered, into the chamber X ., between the outer wall of the 70 valve K ., and the inner wall of the casing T' . And since air, cannot easily or quickly reenter the chamber X ., by way of the passage-way o ., o' ., o'' ., and the valve-seat d' ., by reason of the fact, that the valve D ., is 75 held down, upon its valve-seat d' ., by the weight m ., which is attached to the valve-stem d ., it is readily seen, that we have a gradual control, over the air, which is trying to reenter the chamber X ., thereby giving us a gradual, regulated, self-closing of the valve K ., and maintaining the double guard, against leakage, by way of the vent-valve D ., as related above. 80

You will notice that I say,—control over 85 the air, which is trying to reenter the chamber X . The reason for this statement is,— that when the valve K ., begins to close, the tank E ., is practically empty of water, and the valve K ., being so far removed from its 90 valve-seat K' ., there is nothing but air, to find its way, into the chamber X . And also, by way of reference, would say, that the device is so formed, that the contents of the tank E ., is expelled, at some little time, before the valve K ., is closed; thereby allowing for an extra amount of water, to flow from the inlet I ., into the tank E ., and to pass directly, to and through the valve-seat K' ., and thus serve, as the quantity of water 95 needed, to refill the closet bowl, after the closet bowl has been flushed, and before the valve K ., is closed.

The means employed to open the valves D ., and K ., becomes a feature,—not in the 105 way the valves D ., and K ., are opened; but as soon as the valves D ., and K ., are opened, the said means, by releasing the operating handle H ., breaks contact, see Fig. 5., with the said valves, and allows the immediate 110 closure, of the valve D ., by means of the weight m .; thus performing a specific act or function, in leaving the valve K ., suspended, within the casing T' ., see Fig. 5., for a predetermined time, in order to regulate the self-closing of the valve K . 115

With the special features, thus described, my device performs its work, as follows;— In Fig. 2., the valves D ., and K ., are in the closed position. Water is allowed to enter 120 the tank E ., through the inlet I . Into the said tank E ., water will flow, until the air, within the tank E ., has been compressed, to an equal degree, with the water pressure, from the service pipe. As the tank E ., is 125 filled with water and compressing the air therein, as soon as the air and water pressure, within the tank E ., has become of a sufficient pressure, to overcome, the resistance, that is offered, to either air or water, 130

by the close co-adaptation of the outer wall of the tank K., and the inner wall of the casing T', then and not before,—water passing through O', O'', will be forced between the said surfaces of the valve K., and the casing T'; and this forced filtration, between the outer wall of the valve K., and the inner wall of the casing T', will be continued, until the air within the chamber 10 X., will be of the same compression, as the air, within the tank E. This compression of air and water, within the chamber X., will force the valve K., downward, upon its valve-seat K', and assure a positive closure, 15 of said valve K.

In Fig. 3., the operating means, H., S., and B., are shown, as having opened the valve D., and thereby raised the valve-stem d., so as to expose the opening o., above the 20 top-surface of the valve K., and relieving the chamber X., from its pressure of confined air and water, by way of the passage-way o., o', o'', downward, through the valve-seat K'. The quantity of water, that 25 has been confined within the chamber X., is so small, that it is not considered, of a flushing nature. Now, with the pressure removed from the chamber X., by the opening of the valve D., and of the passage-way o., o', o'', 30 a full downward motion of the handle H., will operate the means, H., S., B., d., and m., which will easily push the main valve K., upward into the chamber X., and away from the valve-seat K', see Fig. 4., and allow the 35 contents of the tank E., to pass into the openings O', O'', and directly through the valve-seat K', into the discharge or flushing pipe, at O.; and in this act of discharging, the water in the tank E., is forced into the 40 flushing pipe, under the heavy compression of air, aforesaid, that has been confined, within the tank E.

As soon as the valve K., Fig. 5., has been pushed up, into the casing T', and the han-

dle H., is released, the counter-balance C., 45 returns the handle H., which rotates the spindle S. to which is firmly fixed the finger B., back to their starting position; thereby, breaking contact, with the valve-stem d., which act, allows the immediate closure of 50 the valve D., and simultaneously the inlet opening o., of the passage-way o., o', o'', is dropped back, into the aperture, through which the valve-stem d., passes, by means of the weight m., which is attached to the 55 valve-stem d., and leaves the valve K., suspended within the casing T', as shown in Fig. 5.; and as stated above, the valve K., Fig. 5., will descend, slower or faster, in proportion, to the assembling of the parts T', 60 K., D., d., d', n. n', and m., and thereby return the parts, to their respective positions as shown in Fig. 2, and leaves the device ready, to repeat its work.

From the above description, it will be 65 noticed, that the objects of my present invention, as above mentioned, are fully accomplished.

What I do claim as my invention, and desire to secure, by Letters Patent is,—

A duplex valve comprising an apertured casing inclosing a main valve and an auxiliary valve, said main valve having a gasket secured to its upper portion and forming between the casing and the main valve a 70 packing means, the inner portion of said gasket forming a pliable seat for the auxiliary valve, said auxiliary valve having an apertured stem extending through the main valve and having a stop for engaging said 75 main valve.

In testimony whereof I have signed my name to this specification, in the presence of two subscribing witnesses.

JOHN LINCOLN GISH.
